DRAWING MANDREL OR PLUG

John A. Staples, University City, and Tannie Lewin, Clayton, Mo., assignors to Lewin-Mathes Company, East St. Louis, Ill., a corporation of Delaware

Application June 9, 1941, Serial No. 397,221

5 Claims. (Cl. 205—7)

This invention relates generally to the production of seamless tubing and, more particularly, to a certain new and useful improvement in drawing-mandrels or plugs for the cold drawing production of tubing.

In present conventional cold drawing practice, so far as we are aware, the tubing which is to be drawn is sleeved or strung over a drawing-mandrel or so-called plug which is supported on a relatively long plug-rod or holding-up bar until the swaged or so-called pointed end of the tubing comes into engagement with the forwardly presented end of the drawing-mandrel. The plug-rod or bar is then impelled forwardly under the bias of a heavy spring or other shifting structure for projecting the pointed end of the tubing through the drawing-die for engagement by the jaws of the drawing-carriage.

In such practice, loss of time and material, as well as damage to tools and machinery, has resulted by reason of a tendency for the pointed end of the tubing to crack or break off as the tubing initially enters the die at the beginning of the second or further drawing operation on the same point. In addition, for some now unexplained reason, a very noisy vibratory quivering action, commonly referred to as "chattering," is frequently encountered as the tubing is pulled through the die, resulting in accelerated break-down of the tools, as well as producing non-uniformity and impairing ridges or surface markings in and upon the inner and outer periphery of the finished tubing.

Our present invention has hence for its primary object the provision in cold drawing apparatus of a mandrel or plug so uniquely formed and constructed as to eliminate cracking or breaking-off of the pointed ends of tubing as the tubing enters the drawing-die and also obviate "chattering" with all its attendant and resulting defects in the finished tubing.

And with the above and other objects in view, our invention resides in the novel features of form and construction of the drawing-mandrel or plug presently described and pointed out in the claims.

In the accompanying drawings (two sheets):

Figure 1 is a perspective view of a drawing-bench comprising a plug-rod or holding-up bar equipped with a drawing-mandrel or plug constructed in accordance with and embodying our present invention;

Figure 2 is a perspective view of a primary drawing plug adapted for use in the first pass or draw to which the tubing is subjected;

Figure 3 is a perspective view of a secondary drawing-plug of our invention adapted for use in all successive passes or draws to which the tubing is subjected;

5 Figure 4 is a diagrammatic view illustrating the primary stage in cold drawing operations employing the primary drawing-plug of Figure 2; and

Figures 5, 6, 7, 8, and 9 are progressive diagrammatic views of successive stages in cold drawing operations employing drawing-mandrels or plugs of our invention.

Referring now in more detail and by reference characters to the drawings, which illustrate a 15 preferred embodiment of the present invention, A designates a conventional drawing-bench, suitably located upon which is a rigid mounting 1 for a removable or renewable drawing-die 2. Mounted for travel on the bench A, is a draw-carriage 3 provided with suitable jaws 4 for gripping the tube T or other work at its pointed end t and having means for engagement with an 20 endless traveling draw-chain 5 for pulling movement of the carriage 3 and gripped tube T along the bench A and away from the die 2 during a drawing operation. Extending rearwardly from the die-mounting 1, is a pair of horizontally disposed guide-rods 6 fixed at their rear end in a support 7 and supported intermediate their ends by a plurality of spaced intermediate plates or the like 8 and preferably connected by arcuate cross tie-members 9.

Mounted on the support 7 in axial alignment with the die 2, is a plunger-cylinder 10 connected by means of suitable pipes or conduits 11 in a hydraulic system (not shown), in which is included a suitable control valve positioned for convenient manipulation by the machine-operator.

40 Working in the cylinder 10, is a piston 12, and fixed at an end to the piston 12, is an outwardly extending piston-rod 13 connected at its other or outer end to a rod or bar 14 suitably elongated to extend at its free end forwardly intermediate the rods 6 and over the supports or plates 8 to a point adjacent the drawing-die 2, the rod or bar 14 at such extremity being formed or provided with a tapped chamber or socket, as at 14', for interchangeable connection with drawing-plugs 50 or mandrels B, B'.

The so-called primary mandrel or plug B adapted for use in the initial pass or draw is dimensionally sized for complementary drawing action with the initial drawing-die 2 and consists 55 of an accurately turned cylindrical section 15 of

hardened tool steel formed or provided at one end with an accurately machined co-axial threaded shank 16 diametrically sized for snug-fitting engagement in the socket 14' of the rod or bar 14. At its opposite end, the cylindrical plug-section 15 is preferably slightly chamfered circumferentially, as at 17, and provided with a flat end face 18.

In the initial draw or pass, the cylinder 10 is hydraulically retracted so as to shift the rod 14 and its associated plug B rearwardly away from the die 2. The raw tube T, having been swaged in a conventional swaging machine (not shown) in the formation of a so-called pointed end *t*, is suitably fed or strung over the plug B and the rod 15 or bar 14 until the inner oblique face of the pointed tube-end *t* comes into impinging engagement with the chamfered margin 17 of the plug B and is positioned in registering alignment with the entrant end of the die 2, substantially in the manner shown in Figure 4.

The cylinder 10 and its associated piston 12 are then hydraulically actuated to shift the rod or bar 14, together with the plug B and the supported tube-section T, forwardly, projecting the pointed-end *t* of the tubing T through the die 2 for engagement in and by the draw-carriage jaws 4 and positioning the plug B for tube-reducing or drawing co-operation with the die 2, whereupon, the pointed tube-end *t* being securely gripped by the draw-carriage jaws 4, the draw-carriage 3 is engaged with the draw-chain 5 and pulled forwardly, thereby drawing the section of tubing T through the die 2 and over the plug B.

At the beginning of this initial drawing operation, the plug B moves forwardly under the influence of the piston 12 and concurrently with the movement of the tube T until, as stated, the plug B is co-operatively located with respect to the die 2. Momentarily, therefore, the annular space between the plug B and the die 2 is greater than the ultimate desired thickness to which the tubing T is being reduced, with the result that an annular shoulder, ridge, or ledge, commonly termed a collar, *s* is formed in the pointed tube-end *t*, all as best seen in Figure 5. It will, of course, be understood that such first drawing operation is repeated, the same or a similar plug B and die 2 being used or employed for each successive section of the tubing making up the particular batch of tubing being run at any one time.

When the initial draw or pass has been completed on the entire run of tubing, the plug B and die 2 are removed from the rod or bar 14 and die-supporting plate 1, respectively, and replaced by a secondary plug-die set B', 2'; or the first drawn tube-sections may be suitably transported or conveyed to a section bench equipped with a plug-die set B', 2'.

The die 2' is substantially conventional and in all respects similar to the die 2, except reduction in inner diametral size. The plug B', however, is precisely machined from suitable hardened tool steel and preferably integrally includes a cylindrical body section 15' having an external diametral size precisely equal to the desired internal diametral size to which the tubing section T is to be reduced during the second pass or draw. Extending co-axially from one end of the cylindrical section 15', is an externally threaded shank 16' substantially identical in all respects to the shank 16 of the primary plug B.

Extending co-axially from the opposite end of the plug body-section 15', is a preferably cylin-

drical diametrically reduced extension or so-called nose 18 having a length and diameter so related to the degree of taper of the pointed tube-end *t* that, when the latter is strung or sleeved over the plug B' and the rod or bar 14 incident to the beginning of the second pass, the nose 18 at its free end will come into impinging engagement with the pointed tube-end *t* in a plane in which the outside diametral size of the tapering pointed end *t* is substantially smaller than the effective drawing diameter of the die 2', thereby positioning the forward annular margin *m* of the plug body-section 15' rearwardly of the collar or shoulder *s* formed in the pointed tube-end *t* as a result of the preceding pass or draw, as shown in Figure 6. Thus the tapering or pointed tube-end *t* which is of indeterminate wall thickness and includes the collar *s* will pass through the die 2' without any reduction in wall thickness that is to say, in the manner of a so-called "no-draw" pass.

The hydraulic cylinder 10 is again actuated to shift the rod or bar 14, together with the plug B' and its supported tubing section T forwardly, thereby projecting the pointed end *t* of the tubing section T being worked through the die 2' for re-engagement in or by the jaws 4 of the draw-carriage 3, and the second pass or draw being then accomplished in the same manner as the described first pass or draw. The mandrel or plug body-section 15' thus moves up into engagement in the die 2' concurrently with the forward portion of the tubing section itself and reaches operative drawing position with respect to the die 2' after the pointed tube-end *t* has moved through the die 2', thus forming a second annular shoulder or collar *s'* upon the inner periphery of the tubing at a point spaced rearwardly from the first shoulder or collar *s*, all as best seen in Figure 7.

If desired, a tertiary plug-die set B'', 2'', may be provided, in which event the same are substantially similar in all respects to the plug-die set B', 2', except again, for reduced size, the tubing being worked being accordingly further reduced in diameter and wall-thickness and in the draw being provided upon its inner periphery with a third shoulder or collar *s''*, as indicated in Figure 9.

Should it be desired to subject the tubing section T to further successive passes for further reduction in diameter and wall thickness, additional plug-die sets of suitable relative size will be substituted or employed, each set being likewise substantially similar to the set B', 2', and in each case the respective plugs B' are provided with forwardly projecting noses or extensions 18 so shaped and sized as to, when in impinging engagement with the pointed end *t* of the tubing being worked or reduced, locate the cylindrical body-portion 15' of the particular plug for engaging the inner wall of the tubing section T rearwardly of the internal collar or shoulder *s* formed as a result of the preceding draw.

From practice and experience, we have found that mandrels or plugs B' eliminate "chattering" of the tubing, efficiently obviate breaking or cracking-off of the pointed tube-ends, and effect the production of tubing of uniform characteristics.

It should be understood that changes and modifications in the form, construction, arrangement, and combination of the several parts of the apparatus may be made and substituted for those herein shown and described without de-

parting from the nature and principle of our invention.

Having thus described our invention, what we claim and desire to secure by Letters Patent is:

1. A seamless tube drawing-mandrel integrally including a substantially cylindrical body-section and a diametrically reduced cylindrical nose-portion projecting forwardly from the body-section for impinging engagement at its free-end margin with the pointed end of a tubing-section being drawn for preventing engagement of the body-section with such tubing-section during the initial die-positioning of the mandrel for a drawing operation.

2. A seamless tube drawing-mandrel constructed of hardened tool steel and integrally including an accurately turned cylindrical body-section having an internal diametrical size to which the tubing is to be reduced and a diametrically reduced cylindrical nose-portion projecting forwardly from the body-section and elongated for impinging engagement at its free-end margin with the pointed end of a tubing-section being drawn for preventing engagement of the body-section with such tubing-section during the initial die-positioning of the mandrel for a drawing operation.

3. A seamless tube drawing-mandrel integrally including an accurately turned cylindrical body-section having an internal diametrical size to which the tubing is to be reduced and a diametrically reduced cylindrical nose-portion projecting forwardly from the body-section and having a length such that a tubing-shoulder resulting from a previous pass to which the tubing

has been subjected will be disposed intermediate the free margin of the nose-portion and the forward end of the body-section when the mandrel is positioned within the tubing for a drawing operation.

4. A seamless tube drawing-mandrel integrally including an accurately turned cylindrical body-section having an internal diametrical size to which the tubing is to be reduced and a diametrically reduced cylindrical nose-portion projecting forwardly from the body-section and having a length in relation to its diameter such that a tubing-shoulder resulting from a previous pass to which the tubing has been subjected will be disposed intermediate the free margin of the nose-portion and the forward end of the body-section when the mandrel is positioned within the tubing for a drawing operation.

5. A seamless tube drawing-mandrel constructed of hardened tool steel and integrally including an accurately turned cylindrical body-section having an internal diametrical size to which the tubing is to be reduced and a diametrically reduced cylindrical nose-portion projecting forwardly from the body-section and having a length and diametrical size for impinging engagement at its free-end margin with a tubing-section being drawn for spacing such tubing-section at its inner face from said body-section as the pointed end of the tubing-section initially comes into engagement with a companion die.
